UNITED STATES PATENT OFFICE.

RUDOLPH L. BROWN, OF CHICAGO, ILLINOIS, ASSIGNOR TO THE NATIONAL LOCK WASHER COMPANY, OF NEWARK, NEW JERSEY, A CORPORATION OF NEW JERSEY.

TICKET-HOLDER FOR CAR-CURTAINS.

1,214,006.

Specification of Letters Patent.

Patented Jan. 30, 1917.

Application filed January 26, 1912. Serial No. 673,531.

To all whom it may concern:

Be it known that I, RUDOLPH L. BROWN, a citizen of the United States, residing in the city of Chicago, in the county of Cook, and 5 State of Illinois, have invented certain new and useful Improvements in Ticket-Holders for Car-Curtains, of which the following is a full, clear, and exact description, such as will enable others skilled in the art to which 10 it pertains to make, construct, and use the same, reference being had to the accompanying drawings, and to letters of reference marked thereon, forming a part of this specification.

15 This invention relates to certain new and useful improvements in ticket holders primarily designed for use in connection with the window curtains so extensively used on cars, and the invention has for its object, 20 among others, to provide a simple and inexpensive ticket holder, which shall be provided with means for firmly holding a conductor's check or railroad ticket, so that the same cannot become accidentally disengaged 25 from the holder, and which will at all times be in view of the conductor while passing through the car without disturbing the passenger.

The device preferably consists of a metallic plate of any desired size or shape; it 30 being understood however, that any other well-known material may be substituted, and which may, if desired, be combined with the ordinary face plate commonly used on a car 35 curtain, and secured to the curtain rod or to the curtain in any convenient manner.

The device consists of a rigid metallic plate so formed that one portion of the plate 40 will conform to the shape of that part of the curtain to which it is attached, and another portion curved from the first portion and the curtain, so that an acute angular space will be created between the curtain and the curved portion or lip, into which space the 45 end of a railroad ticket may be thrust and be securely wedged and held.

The invention is clearly illustrated in the accompanying drawings, in which—

Figure 1 represents a front elevation of 50 my improved device. Fig. 2 represents an end elevation of the same. Fig. 3 represents another form of my improved device. Fig. 4 represents an end elevation of the same. Fig. 5 represents a front elevation of a car 55 curtain, having attached thereto my im-

proved device. Fig. 6 represents an enlarged sectional view taken on lines $x-x$ of Fig. 5; and Fig. 7 represents a front elevation of my improved device as illustrated in Figs. 5 and 6.

Similar letters of reference refer to like parts throughout the specification and drawings.

The plate or holder shown in the drawings is preferably made from sheet brass, or other 60 suitable material, and may be perforated or ornamented and is of a shape which lends itself readily to manufacture by the use of suitable punches and dies from ordinary sheet metal.

One form of the ticket holder is illustrated in Figs. 1 and 2, where a portion of the plate a is shaped to conform to the shape of the curtain where the ordinary curtain rod rounds out the curtain, and the upper 70 parts $k-k$ are shaped to conform to that part of the curtain immediately above the rod, and the lips h curve from the curtain forming an acute angular space between the curtain f and lip h into which a railroad 75 ticket may be thrust and held by the wedging action. The parts $k-k$ resting against the face of the curtain prevent wear on the curtain.

Figs. 3 and 4 simply show a modification 80 of Figs. 1 and 2, wherein the whole upper portion of the plate is curved from the curtain with the exception of the tongues $l-l$, which rest against the curtain to prevent 85 wear on the face of the curtain, in the same 90 manner as the parts $k-k$ in Figs. 1 and 2.

Another form of the ticket holder is shown 95 in Figs. 5, 6 and 7 of the drawings, wherein the lower portion is shaped to conform to the shape of the curtain where the curtain rod rounds out the curtain. In this form, the 100 entire upper portion h of the plate is curved away from the curtain, forming an acute angular space between the curtain and the lip h .

In all the forms shown, the principle is the same, namely, a space is created between the curtain and the lip which is so acute that it will hold a ticket firmly by wedging the end of same into this space. The mouth of 105 the space is sufficiently wide to make it convenient to thrust a ticket in.

Experience has demonstrated that the device above described is a highly efficient one, and I do not wish to confine myself to the 110

exact configurations or dimensions of the holder shown in the drawings, as many changes may obviously be made without departing from the spirit of my invention, nor do I wish to be confined to the material, capacity or shape of the device, it being obvious that the device will readily lend itself to be shaped into any form of holder, and such departures from what is herein described and claimed, not involving invention, I consider as within the scope and terms of my claim.

I claim:

An integral ticket holder adapted for use

with a car curtain having a rod therein, said holder having a portion at one end thereof curved to conform to the rod and provided in said portion with an opening whereby it may be secured to the rod, and a reversely-curved portion at the other end of said holder adapted, in conjunction with the curtain, to form a pocket to hold a ticket.

This specification signed and witnessed this 22nd day of January, 1912.

RUDOLPH L. BROWN.
